[57] CLAIM

The ornamental design for a truck roof fairing, as shown and described.

DESCRIPTION

FIG. 1 is a side elevation view of a truck roof fairing showing our new design, it being understood that the opposite side is a mirror image thereof and that the broken lines are for illustrative purposes only and form no part of the claimed design;

FIG. 2 is an enlarged front elevation view thereof;

FIG. 3 is a top plan view thereof; and

FIG. 4 is an enlarged rear elevation view thereof.

FIG.-1.

FIG.-2.

FIG.-3.

FIG.-4.
